Primary Examiner — Stacia A Cadmus(74) *Attorney, Agent, or Firm* — RatnerPrestia(57) **CLAIM**

The ornamental design for a wheel for motor vehicle, as shown and described.

DESCRIPTION

FIG. 1 is a front perspective view of a wheel for motor vehicle;

FIG. 2 is a front elevation view thereof; and,

FIG. 3 is a top plan view thereof.

The broken line showing of the wheel for motor vehicle is for the purpose of illustrating portions of the wheel for motor vehicle and forms no part of the claimed design.
